TABLE COUPLING APPARATUS

John L. Drake, Toledo, Ohio, assignor to Libbey-Owens-Ford Glass Company, Toledo, Ohio, a corporation of Ohio

Application June 29, 1929, Serial No. 374,883

8 Claims. (Cl. 213—100)

This invention relates to improvements in apparatus designed particularly for use in what is known as the continuous system for grinding and polishing sheet glass wherein the glass sheets, mounted upon cars or tables, are ground and polished in a straight-away operation by passing them successively beneath a series of grinding and polishing units.

The invention has for its principal objects the provision of an improved type of coupling means for securing the adjacent cars or tables together and in the provision of novel means for controlling the coupling and uncoupling of the cars or tables by the operator of an operating car which is used to pull the cars or tables apart subsequent to the uncoupling thereof and to push them into abutting relation prior to coupling, said operator being able to accomplish the coupling and uncoupling of the cars or tables without assistance from others or without leaving the operating car. Another object is the provision of apparatus for controlling the coupling and uncoupling of the tables including means carried by the operating car for maintaining the coupling means in an uncoupled position during either a pushing or pulling of the table.

Other objects and advantages of the invention will become more apparent during the course of the following description when taken in connection with the accompanying drawings.

In the drawings forming a part of this application and wherein like numerals are employed to designate like parts throughout the same.

Fig. 1 is a top plan view of the adjacent ends of two adjoining cars or tables broken away to show the improved coupling means associated therewith.

Fig. 2 is a side elevation partially in section of the operating car for controlling the coupling and uncoupling of the tables, and

Fig. 3 is a top plan view thereof partially broken away to show parts of the operating mechanism.

In the drawings is illustrated a plurality of work cars or tables 5 mounted upon wheels 6 rolling along a trackway 7. In the continuous system for grinding and polishing glass sheets, a desired number of tables 5 are adapted to be coupled end to end and are movable along the trackway 7 to carry glass sheets, mounted thereupon, first beneath a series of grinding units and then beneath a series of polishing units.

In the present instance, each work table 5 comprises a flat top 8 upon which the glass sheets to be surfaced are adapted to be secured and a bottom 9 spaced from top 8 and connected there-

with at each end by a vertical connecting wall or web 10 including the inwardly extending central portion 11 and the transverse side portions 12 and 13. Slidably mounted within each of the transverse portions 12 and 13 of web 10 is a horizontal pin 14 provided at its outer end with a substantially U-shaped bracket 15 between the spaced legs 16 of which is carried a shaft 17 upon which is mounted a hook 18, said hook being provided with an off-set trip lug or projection 19 received within the recess 20 in web 10.

Carried by the opposite end of pin 14 is a bracket 21 having spaced ears 22 between which is pivoted as at 23 one end of a transversely arranged operating or rocker arm 24, said arm being fulcrumed intermediate its ends upon the shaft 25. Encircling the pin 14 is a compression spring 26 bearing at its opposite ends against the transverse web portion 12 or 13 and bracket 21 so as to normally draw and hold the hook 18 inwardly. Each rocker arm 24 is provided at its inner end with a substantially U-shaped portion 27 adapted to fit about the actuating rod 28 slidably received through the central portion 11 of web 10 and formed at its adjacent end with a head 29. The operating rod 28 extends longitudinally of the table and is associated at the opposite end thereof with a similar coupling mechanism. Fixed to the rod 28 outwardly of rocker arms 24 is a collar 30. The coupling means at the opposite end of the table is exactly of the same construction with the exception that the hooks face in the opposite direction as is necessary so that the cooperating hooks at the adjacent ends of the two adjoining tables may be interengaged with one another to couple the tables together. Thus, the hooks 18 at one end of the table and the hooks 31 carried at the adjacent end of the adjoining table face in opposite directions.

In operation, when the two tables are properly coupled together the adjacent hooks 18 and 31 interlock one another and the various parts assume the positions indicated by the full lines in Fig. 1. However, when it is desired to uncouple the tables, the actuating rod 28 is pulled inwardly so that the collar 30 engaging the inner ends of rocker arms 24 will function to rock said arms about shafts 25 and thus force the pins 14 outwardly against the action of compression springs 26. Upon outward movement of pins 14 and hooks 18 will be carried therewith and trip lugs 19 abutting the front end walls or recesses 20 will cause or effect a tripping of the hooks 18 to rock them laterally out of engagement with hooks 31.

31. When it is again desired to couple the tables, the actuating rod 28 is also pulled inwardly to first move the hooks 18 forwardly and laterally to their broken line positions in Fig. 1, after which 5 the table is moved to abut the adjacent table and the rod 28 released whereupon the springs 26 will function to draw the pins 14 and hooks 18 inwardly and the trip lugs 19 then abutting the inner walls of recesses 20 will rock the hooks 18 to engage hooks 31. The compression springs 26 act to hold the hooks 18 and 31 in firm interlocking engagement. The rod 28 is therefore associated with the coupling means at opposite ends of the table and upon movement in one direction is adapted 10 to effect the operation of the coupling means at one end of the table and upon movement in the opposite direction will cause the operation of the coupling means at the opposite end of said table.

For the purpose of controlling the coupling and uncoupling of the cars or tables, there is provided 20 an operating car 33 mounted upon wheels 34 and movable along the trackway 7. The operating car 33 has mounted thereupon a horizontal sliding member 35 to the forward end of which is pivoted as at 36 a hook member 37 adapted for engagement with the operating rod 28. The sliding member 35 is suitably supported for horizontal forward and backward sliding movement and has secured to its rear end a screw 38 threaded 25 through a spiral gear 39 mounted between bearings 40 through which said screw extends. The spiral gear 39 is adapted to be driven from a second spiral gear 41 carried by shaft 42 driven from motor 43 through suitable reduction gearing 30 so that upon operation of the motor the sliding member 35 can be moved inwardly or outwardly as desired. Mounted beneath and slidably carried by the slide member 35 is a slide bar 44 to the inner end of which is pivoted as at 45 a lever 46 fulcrumed intermediate its ends as at 47 and carrying a pawl 48 adapted to engage the toothed segment or ratchet 49. Upon rocking movement of the lever 46 about its pivot 47 the slide bar 44 can be moved inwardly or outwardly 40 relative to the slide member 35.

It will, of course, be readily understood that in the continuous system for surfacing sheet glass, a plurality of tables are coupled together end to end in a manner to form an unbroken line or train, said tables being movable upon rails and being adapted to carry the glass sheets beneath a series of grinding and polishing units. The tables are coupled together at the forward end of the line and uncoupled at the opposite end thereof. In other words, as one table is added at the forward end of the line, one table is being removed from the opposite end of said line. Therefore, an operating car can be provided at each end of the line of tables, the operating car at the forward end being used for coupling the tables together and the operating car at the opposite end being employed to uncouple the tables. When it is desired to uncouple the tables, the operating car 33 is moved along the trackway 7 until its forward end abuts the end of the adjacent table, after which the slide member 35 is moved forwardly until the hook 37 thereof is positioned beneath the adjacent end of operating rod 28 inwardly of the head 29 thereof. The lever 46 is then rocked about its pivot 47 to move the slide bar 44 outwardly and this bar engaging hook 37 will rock the same upwardly about its pivot 36 and hold it in engagement with rod 28 inwardly of head 29. The motor 43 is then driven to 60 thread the screw 38 rearwardly through spiral 75

gear 39 so as to draw the slide member 35 and slide bar 44 rearwardly as a unit. Upon such rearward movement of slide member 35 the hook 37 thereof engaging head 29 of operating rod 28 will draw said operating rod therewith so that 80 the collar 30 at the opposite end thereof engaging rocker arms 24 will effect the disengagement of hooks 18 from the hooks 31 on the adjacent table in the manner above described whereby to effect the uncoupling thereof. The table 5 with which the operating car 33 is associated can then be pulled away from the adjacent table upon rearward movement of the operating car and it will be apparent that with such an arrangement the coupling means will be held in uncoupled or inoperative position or, in other words, the hooks 18 will be held in their broken line position indicated in Fig. 1 upon either a pushing or pulling of the tables. Upon rearward movement of the operating car to separate the tables, the bar 28 and head 29, together with the hook 37, constitute a coupling means for connecting the operating car and adjacent table together. When it is desired to couple the tables together, the coupling means is first moved into uncoupled position in 95 the manner above described after which the table 5 is pushed by the operating car 33 to abut the adjacent table to which it is to be coupled after which the slide bar 44 is moved rearwardly with respect to the slide members 35 to permit hook 100 37 to drop downwardly out of the path of head 29 of operating rod 28 whereupon the compression springs 26 will draw the operating rod forwardly and rock the arms 24 about shafts 25 to move the hooks 18 into engagement with hooks 31. Thus, 110 the operator stationed upon the operating car can effect the coupling and uncoupling of the tables without assistance from others and without leaving the car.

It is to be understood that the form of the invention herewith shown and described is to be taken as the preferred embodiment of the same, and that various changes in the shape, size and arrangement of parts may be resorted to without departing from the spirit of the invention or the 115 scope of the subjoined claims.

I claim

1. In coupling means for cars or tables, coupling apparatus arranged at each end of the table and including a pivotally mounted hook, a rocker 125 arm also arranged adjacent each end of the table, connections between each rocker arm and its respective hook, an operating rod extending longitudinally of the table and adapted upon movement in one direction to actuate one of the rocker arms whereby to effect swinging of the respective hook about its pivot and when moved in the opposite direction to actuate the rocker arm at the opposite end of the table to effect swinging movement of the respective hook, and means carried by the table for causing the swinging movement of said hooks upon actuation of said rocker arms.

2. In coupling means for cars or tables, coupling apparatus arranged at each end of the 140 table and including a pivotally mounted hook having a trip lug, a rocker arm also arranged adjacent each end of the table, connections between each rocker arm and its respective hook, an operating rod extending longitudinally of the 145 table and adapted upon movement in one direction to actuate the rocker arm at one end of the table to effect a tripping of the respective hook and when moved in the opposite direction to actuate the rocker arm at the opposite end of the 150

- table to effect tripping of the respective hook, and stationary means carried by the table and engageable by said trip lugs for causing the tripping of said hooks upon actuation of said rocker 5 arms.
3. In coupling means for cars or tables, coupling apparatus arranged at each end of the table and including a plurality of pivotally mounted hooks, a plurality of rocker arms also carried by 10 said table adjacent each end thereof, connections between said rocker arms and hooks, a rod extending longitudinally of the table and adapted upon movement in one direction to actuate the rocker arms to effect swinging of the hooks simultaneously at one end of the table and upon movement in the opposite direction to actuate the rocker arms at the opposite end of the table to effect simultaneous swinging of the respective hooks, and means carried by the table for causing 15 the swinging movement of said hooks upon actuation of said rocker arms.
4. In coupling means for cars or tables, coupling apparatus arranged at each end of the table and including a plurality of pivotally 20 mounted hooks, each having an offset trip lug, a plurality of rocker arms carried adjacent each end of the table, connections between the rocker arms and the respective hooks, a rod extending longitudinally of the table and adapted upon sliding movement in one direction to actuate the rocker arms at one end of the table to effect tripping of the respective hooks simultaneously and upon movement in the opposite direction to 25 actuate the rocker arms at the opposite end of the table to effect simultaneous tripping of the respective hooks, and stationary means carried by the table and engageable by the trip lugs for causing the tripping of said hooks upon actuation of said rocker arms.
5. In coupling means for cars or tables, coupling apparatus arranged at one end of the table and including a hook carried by said table and movable longitudinally thereof, means for pivotally mounting said hook to swing laterally about a vertical pivot, said hook having a trip lug 30 adapted to engage a portion of the table, a rocker arm, connections between said rocker arm and hook, and a slid able rod having means engaging the inner end of said rocker arm for rocking it in a manner to move the hook forwardly and cause 35 it to be tripped by the trip lug and thus swung laterally about its pivot.
6. In coupling means for cars or tables, coupling apparatus arranged at one end of the table and including a plurality of pivotally mounted hooks carried by said table and movable longitudinally thereof, means for pivotally mounting said hooks to swing laterally, means for simultaneously moving the hooks forwardly, means for tripping said hooks during forward movement thereof to swing the same laterally about their pivots, spring means tending to draw the hooks inwardly upon the release of the forward moving means, and means for swinging the hook laterally in the opposite direction during inward movement thereof to return it to its initial position. 40
7. In coupling means for cars or tables, coupling apparatus arranged at one end of the table and including a hook carried by said table and movable longitudinally thereof, means for pivotally mounting said hook to swing laterally about a vertical pivot, said hook having a trip lug 45 adapted to engage a portion of the table, a rocker arm, connections between said rocker arm and hook, and a slid able rod having means engaging the inner end of said rocker arm for rocking it in a manner to move the hook forwardly and cause 50 it to be tripped by the trip lug and thus swung laterally about its pivot.
8. In coupling means for cars or tables, coupling apparatus arranged at one end of the table and including a plurality of hooks carried by 55 said table and movable longitudinally thereof, means for pivotally mounting said hooks to swing about vertical pivots, each hook having a trip lug adapted to engage a portion of said table, a pair of rocker arms, one for each hook, connections 60 between said rocker arms and the respective hooks, and a slid able rod passing between and having means engaging the inner ends of said arms for rocking them in a manner to simultaneously move the hooks forwardly and cause 65 them to be tripped by the trip lugs and thus swung laterally about their pivots.
